TYPEWRITING MACHINE

Jesse A. B. Smith, Stamford, Conn., assignor to
Underwood Elliott Fisher Company, New York,
N. Y., a corporation of Delaware

Application December 30, 1938, Serial No. 248,489

5 Claims. (Cl. 197—63)

This invention relates to margin and tabulator stop mechanisms for typewriters and more particularly to devices for selecting certain groups of stops to produce typed matter having margins, date line, signature or other indentations, arranged in a prescribed manner.

In the typing of correspondence it is desirable to arrange the typed matter on the sheet with a view to symmetry and proportion so that the finished typing presents a neat appearance, with the typing arranged in a generally central position on the sheet and in proportion corresponding to the length of the typed matter. For example, in a relatively short letter, a suitable length of the typed line and, correspondingly, the indentation for the date line and signature, may be determined so that the body of the letter is narrowed in width by selecting a relatively short length for the typed line. Conversely, in a lengthy letter, the length of the typed line selected should be adequate to assure the typing of the letter in a central area on the sheet, in this instance choosing a greater line length and corresponding indentations to produce the desired arrangement of the typed matter on the sheet.

A mechanism affording such a selection of line lengths and tabular indents is shown and described in my Patent No. 2,131,150, issued September 27, 1938, wherein several groups of margin stops, and several groups of tabulator stops are each arranged on rotatable members and may be selectively disposed to coact with corresponding counter-stops upon rotation of the stop-carrying members to predetermine a certain line-length and corresponding indentations, as well as column-defining tabular positions when required. In such devices, however, the operator must exercise some care in setting the stop mechanism to be certain that the desired group of stops is selected.

It is an object of the present invention to provide a selective stop-setting mechanism having a key operated selector device whereby the preselection of a particular group of stops may be effected with dependable facility.

Another object of the invention is to provide a margin-stop or tabulator-stop selecting device affording a selection of various prescribed stop set-ups on stop-carrying members, and presenting an array of selector keys, the operation of any key of which, preceding the actuation of the stop-carrying members, will assure the arrest of the desired group of stops in accurate position for cooperation with the counter-stops,

whereby the typist may be assured that the desired set of stops is in effective position and that the carriage will be stopped during the subsequent typing, at such line-length determining positions and/or tabulating positions as are indicated by the particular selector key operated.

Other features and advantages will herein-after appear.

In the drawings—

Figure 1 is a fragmentary perspective view of the selective margin and tabulator-stop mechanism incorporating the stop selector device and forming the preferred embodiment of the invention.

Figure 2 is a sectional view taken on the plane of the axes of the stop-carrying members, certain of the parts being shown in elevation.

Figure 3 is a fragmentary perspective view of the stop selector device, portions thereof being broken away to facilitate illustration.

Figure 4 is a fragmentary sectional view through the typewriter at a fore-and-aft vertical plane thereof, showing the several mechanisms associated with the platen carriage controlling the movements thereof in typing.

Figure 5 is a fragmentary elevational view of the right end of the typewriter carriage showing the gearing of the stop-setting mechanism.

Figure 6 is a transverse sectional view taken on the line 6—6 of Figure 2, and

Figure 7 is a transverse enlarged sectional view taken on the line 7—7 of Figure 2, portions of the carriage end plate being broken away to reveal the mechanism of the selector device.

Referring now more particularly to Figures 1 and 4, a platen 9 is rotatably mounted on a carriage 10 arranged for endwise movement transversely of the typewriter on trackways 11. The platen carriage 10 is actuated during typing by the usual drum spring, not shown, this movement of the carriage being under control of the usual letter-feed mechanism 12, including a rockable member 13 cooperating with an escape wheel 14 carried on a shaft 15 having a gear 16 thereon in mesh with a rack 17 fixed to the carriage frame 10, all in the well known manner. The return movement of the carriage 10 is manually actuated, against the power of the mentioned spring.

The line-length determining positions of the carriage are controlled by the engagement of adjustable margin-stops 20 with a margin counter-stop 21. The counter-stop 21 may move a limited distance leftward to the position shown in phantom in Figure 1, when engaged by a

rightward margin stop 20, to actuate the usual line-end key-lock device, not shown. The rightward margin-stops 20 may also actuate the usual line-end-indicating device, not shown. The margin-stops 20 toward each end of the carriage are beveled in appropriate directions so that same may pass the counter-stop 21 during movement of the carriage in either direction when the counter-stop 21 is in position beyond either stop 20, as when typing in margins, the bevels 10 of the margin-stops serving to cam the counter-stop rearwardly in passing same, after which the counter-stop 21 springs back to effective position intermediate the margin stops.

The carriage may be arrested in other positions intermediate or beyond the line-length-determining positions, by tabulator stops 22 cooperating with one of a series of tabulator blades or counter-stops 23 shown more clearly in Figure 4, in the usual manner, each of the tabulator blades having one of a series of key-levers 24 fulcrumed at 25, engaging the tabulator blade at its rear end, to move the blade into the path of a tabulator stop 22. A spring 26 for each tabulator blade 23 restores the blade to ineffective position upon release of the tabulator key-lever 24.

Each tabulator blade 23 has a part engageable with a swingable cross-bar 27 having an arm 28 connected by a link 29 with the letter-feed mechanism 12. As any one of the tabulator blades 23 is moved to effective position, the resultant swinging of the cross-bar 27 causes the letter feed mechanism to momentarily free the escapement wheel 14 and thus release the carriage 10 to the power of the mentioned carriage actuating spring, the carriage moving until same is checked by the engagement of one of the tabulator stops 22 with the effective tabulator blade 23, all in the well known manner.

As afore indicated, the carriage control mechanism provides a selection of different groups of line-length-determining stops 20 which, as shown more clearly in Figure 1, are arranged in pairs, each stop being adjustably carried on a rotatable member or multifaced rack bar 30. It is to be noted that the respective pairs of stops 20 representing different line lengths are each carried on a different face of the rack bar 30, so that each pair of stops projects from the rack bar 30 at an angle different from the other pairs of stops. The rack bar 30 is rotatably mounted, preferably in the end plates of the carriage 10, so that by rotation of the rack bar, any one pair of stops may be selectively disposed for cooperation with the counter-stop 21, the effective pair of stops being thus disposed to project rearwardly from the rack bar 30 in the path of the counter-stop 21, see Figure 4.

The tabulator stops 22 are similarly arranged in a series of groups, each stop of each group being adjustably carried on a rotatable member or multifaced rack bar 31. Each group of tabulator stops represents a certain tabular form, or certain line indentations as may be required for the date line, signature or like indented typing. Each group of tabulator stops is carried on a different face of the rack bar 31 so that each group projects from the rack bar 31 at a different angle from each other group. The rack bar 31 is rotatably mounted, preferably in the end plates of the carriage 10 and arranged so that rotation of the rack bar will present any one group of tabulator stops for cooperation with the series of tabulator blades 23.

The stops of each group or pair carried on the rack bars 30, 31 may be arranged in any desired position endwise on the rack bars in that each stop is formed so as to be releasably held in the peripheral grooves of the rack bar. Thus, the stops 20 of each pair on the rack bar 30 may be adjusted relatively to each other to represent a certain line length and margins as required for correspondence of a certain length, and likewise, the stops of each group on rack bar 31 may be adjusted relatively to each other for a prescribed relation of line indentations, or a certain order of tabulating positions required.

It may be here noted that each pair of margin stops 20 is coupled with a certain group of tabulator stops by a system of gearing 33 operatively connecting the two stop-carrying members 30, 31, by which the selection of a certain pair of line-length-determining stops 20 will bring a corresponding group of tabulator or indent-determining stops 22 into effective position. The system of gearing 33 includes gears 34 and 35 fixed to the respective rack bars 30, 31 and operatively connected by an intermediate gear 36 fixed to a control shaft 37 journaled in the carriage end plates as shown more clearly in Figure 2. A suitable actuating knob 38 is arranged to rotate the gearing 33 and therefore the rack bars 30, 31 and shaft 37, the knob 38 being fixed preferably to a projecting end of the rack bar 30. The gearing 33 may have a cover 39 enclosing same in conjunction with the carriage end plate and secured in position against the end plate by the screws shown.

The arrangement and operation of the several mechanisms thus far described are somewhat similar to that shown and described in my said patent, with the exception of the provision of the control shaft 37 and certain other features shown. The combined mechanism thus far described provides for the presentation of any one pair of line-length-determining stops for cooperation with its counter-stop and the concomitant selection of a certain corresponding group of indent-defining tabulator stops for cooperation with the series of tabulator blades 23, this selection being made by actuating knob 38 to concomitantly rotate both rack bars 30, 31 to a position wherein the desired margin and tabulator stops are in condition for cooperation with their respective counter-stops. The rack bars 30, 31 are yieldably detented in each rotative position by a spring detent 40 mounted on the carriage end plate and yieldably coacting with the faces of the rack bar 30.

It is desirable to have the rotative position of the rack bars 30, 31 more positively determined, in a manner to relieve the operator from exercising particular care as to the extent to which the knob 38 is rotated in selecting the desired stop set-up. This easy and positive manner of selectively setting the stops is effected by the selector device shown more clearly in Figures 2, 3 and 7. This device includes a collar 43 carried on the control shaft 37 and adapted for limited rotation thereon, the shaft having a pin 44 fixed thereon and projecting radially into elongate slots 45 in the collar. The collar 43 has a lug 46 thereon forming a detent projecting radially from the shaft 37. A series of indexing or selector stops 47, one for each pair of margin stops, or each group of tabulator stops, are arranged in an annular array in different angular positions about the shaft 37 for selective disposition into the path of the lug 46. Each stop 47 is carried on one of

a series of key stems 48 preferably arranged in lineal array or row, each being slidably carried in the carriage end plate and a casing 49 secured thereto. Complemental mounting blocks 50, 51 held together by screws 52, provide openings in which the key-stems 48 move. The blocks 50, 51 also provide a mounting for a key-interlocking device later described and are secured between the casing 49 and the carriage end plate. The casing 49 includes a cover portion 53 removable to facilitate assembly. Each key stem 48 carries at its outer end a key 54 having suitable indicia, such as the numerals shown, by which to identify the respective pairs of margin stops and the corresponding tabulator stops. Each key stem 48 is 10 detented in depressed position by a spring-pressed ball 55 carried in the block 51 and engaging a depression 56 in the key stem.

From the foregoing, it will be seen that upon operation of any one of the selector keys 54, the corresponding stop 47 of the series will be moved into the path of the lug 46 so that upon manual actuation of the knob 38, both stop bars 30, 31 will be arrested in a predetermined rotative position and the desired pair of margin stops and the desired group of tabulator stops will be positively positioned for cooperation with their respective counter-stops. The limited idle rotation of collar 43 on shaft 37 permits the rotation of knob 38 in either direction in effecting the selection of the carriage stops, it being noted that this idle movement compensates for the combined thickness of the radial lug 46 and the indexing stop 47. That is, when pin 44 is against one end of the slot, the corresponding face of the lug 46 represents the exact radial stop line, for rotation of the shaft 37 in one direction. When the direction of rotation of shaft 37 is opposite, the other face of lug 46 is the effective stop in contact with the opposite face of the indexing stop 47, with pin 44 against the other end of the slot 45; the limited rotation of the collar 43 on the shaft 37 compensating for the thickness of the members 46, 47, so that the shaft 37 is detented in the same radial position, no matter in which direction the shaft is rotated.

A key interlocking device cooperates with the key stems 48 to prevent depressing more than one key 54 at a time, and more particularly, to move an effectively set stop 47, corresponding to the depressed key, to ineffective position, causing the depressed key to be restored to raised position. Each key stem 48 carries a pin 59 projecting laterally therefrom, each pin being disposed in the path of a series of displacement elements or blocks 60 slidably carried in the mounting blocks 50, 51 for movement longitudinally of the row of key stems 48. The corners of the blocks 60 adjacent the pins 59 are each beveled to provide cam surfaces for cooperation with the pins 59. It will be observed that the blocks 60 are confined within the mounting endwise so as to be capable of a limited endwise movement only, either individually or collectively, to the extent of a gap 61 between the end block 60 and a wall formed in the mounting. This gap may occur at either end of the series of blocks or at the abutment of the intermediate block with either end block.

The operation of the key interlocking device is more apparent in Figures 2 and 3 wherein key "1" is depressed and its indexing stop 47 is thus in effective position. The pin 59 associated with key "1" has cooperated with the bevel on the adjacent block 60 so that all blocks are displaced laterally toward one end, leaving the gap 61 at the other end, as shown. It will be seen that this

15 crowding of the blocks 60 toward one end positions each block bevel against the corresponding pin 59 in such relation that the corresponding key stem 48 must be in raised position. Assuming, now, that key "2" is pressed, it will be seen that its pin 59, cooperating with the block bevel, wedges the end block 60 endwise so that the opposite bevel thereof, acting on the pin 59 of key "1", causes said key to be raised. With key "2" depressed, the gap occurs between the end and intermediate blocks 60 at that key. Assuming that while key "2" is depressed, key "4" is subsequently pressed, it will be seen that the two blocks 60 between keys "2" and "4" are moved laterally to close the gap at key "2", the bevel of the intermediate block 60 coaxing with the pin on key "2" to raise the said key. In that each stop 47 is carried on a key stem 48, operation of the key-interlocking device comprising the blocks 60 causes the disabling of one stop 47 concomitantly with the movement of another stop 47 into effective position.

20 Although in the embodiment of the invention herein illustrated, the stop selector device is incorporated with a stop setting mechanism including two rotatable members, one carrying a series of pairs of line-length-determining stops and the other rotatable member carrying a plurality of groups of tabular or indent-defining stops, it will be understood that the stop selecting device may be associated with only one or either of said stop carrying members, if desired.

25 It may be here noted that while the rotative element upon which the stop selector device is directly effective, namely, lug 46 of collar 43, is carried on the control shaft 37, said lug may be regarded as having a positive association with either or both the stop carrying members 30, 31, in view of the positive connection between the shaft 37 and the members 30, 31, afforded by the system of gearing 33. Thus, the lug 46 cooperating with the indexing stops 47 may be considered as being arranged to rotate with either or both of the stop carrying members 30, 31.

30 Although in this application, there is specifically described, one embodiment which the invention may assume in practice, it will be understood that same is shown for the purposes of illustration, and that the invention may be modified and embodied in various other forms without departing from its spirit or the scope of the appended claims.

35 What is claimed as new is:

1. In a selective carriage stop mechanism for typewriters having a stop bar rotatable to present different groups of carriage stops thereon to a counter-stop; means to control the rotative position of said stop bar comprising, a detent rotatable with said stop bar, an array of slidable key stems, one for each group of carriage stops, a manually engageable key carried on each of said stems, and an indexing stop mounted on each of said stems, normally out of the path of said detent, said stems being slidable to selectively present the corresponding indexing stops in the path of said detent.

2. In a selective carriage stop mechanism for typewriters, having a stop bar rotatable to present different groups of carriage stops thereon to a counterstop; means to control the rotative position of said stop bar comprising, a detent normally rotatable with said stop bar, an annular array of indexing stops arranged about the center of rotation of said detent, means movably mounting said indexing stops for setting same

into the path of said detent, and means mounting said detent for limited rotation independently of said stop bar to compensate for the thickness of the effective indexing stop and said detent in rotating the stop bar in an opposite direction.

3. In a selective carriage stop mechanism for typewriters having a stop bar rotatable to present different groups of carriage stops thereon to a counterstop; means to control the rotative positions of said stop bar comprising, a detent rotatably mounted independently of said stop bar, driving connections between said stop bar and said detent for rotation in unison, an annular array of indexing stops about the center of rotation of said detent and normally out of the path thereof, and means slidably mounting said indexing stops for movement axially of said detent to selectively position said stops in the path of said detent.

4. In a selective carriage stop mechanism for typewriters having a stop bar rotatable to present different groups of carriage stops thereon to a counterstop; means to control the rotative position of said stop bar comprising, a detent rotatable with said stop bar, driving connections between said stop bar and said detent for rota-

tion in unison, a lineal array of slidable key stems, one for each group of carriage stops, said key stems being slidable axially of said detent, an indexing stop carried by each of said key stems, said indexing stops being disposed in an annular array about the center of rotation of said detent, normally out of the path thereof and adapted to be selectively positioned in the path of said detent.

5. In a selective carriage stop mechanism having a margin stop bar rotatable to present different groups of margin stops thereon to a counterstop and a tabulator stop bar rotatable to present different groups of tabulator stops thereon to a counterstop; means to determine the rotative position of said stop bars comprising, a rotatable shaft axially parallel with said stop bars, driving means operatively connecting said stop bars and said shaft for rotation in unison, a detent on said shaft and rotatable therewith, an annular array of indexing stops disposed about the center of rotation of said detent, and a series of key stems carrying said indexing stops and slidably mounted for movement axially of said shaft to selectively position said stops in the path of said detent.

JESSE A. B. SMITH.
